UNITED STATES PATENT OFFICE.

ANDREW O. SETHMAN, OF EAST BOSTON, MASSACHUSETTS, ASSIGNOR OF TWO-THIRDS
TO FRANCIS A. SHEA, OF BROOKLINE, MASSACHUSETTS.

HAT-FASTENER.

1,084,758.

Specification of Letters Patent.

Patented Jan. 20, 1914.

Application filed July 11, 1913. Serial No. 778,464.

To all whom it may concern:

Be it known that I, ANDREW O. SETHMAN, a citizen of the United States, and resident of East Boston, county of Suffolk, State of Massachusetts, have invented an Improvement in Hat-Fasteners, of which the following description, in connection with the accompanying drawing, is a specification, like characters on the drawing representing like

10 parts.

This invention relates to hat fasteners of that type which are secured to the inside of the hat, and are provided with hat holding members that are adapted to be inserted into the hair for holding the hat thereon. Hat fasteners of this type are designed to be used in the place of hatpins for holding ladies' hats on their heads.

The object of my invention is to provide 20 a novel hat fastener of this type which is so constructed that all parts thereof which are liable to be caught in the hair are fully protected, and so that it can be very readily attached to any hat.

25 I will first describe a selected embodiment of my invention from which the principle thereof will be readily seen, and will then point out the novel features of the invention in the appended claims.

30 Referring to the drawings Figure 1 is a sectional view of a hat having my improved fastener secured therein, two such fasteners being shown, one in its operative, and the other in its inoperative position. Fig. 2 is 35 an enlarged view of the hat fastener, and taken on substantially the line $x-x$, Fig. 4. Figs. 3 and 4 are side views of the hat fastener showing the hat holding member in different positions, Fig. 4 having a part in 40 section to better illustrate the construction.

45 Fig. 5 is a section on the line $y-y$, Fig. 3. My improved hat fastener comprises a guiding member, a forked hat-holding member slidably mounted in the guiding member, and an attaching member of special construction which has not only the function of providing means for attaching the device to a hat, but has the further function of acting as a protective covering for the guiding member, the head of the hat-holding member and other parts in which there is liability of catching the hair.

50 The hat-holding member is shown generally at 1, and has a forked construction presenting the two arms 2 and 3 that are adapt-

ed to enter the hair when said hat-holding member is in operative position. These arms 2 and 3 are shown as secured to a head 4 which constitutes a handle by which the hat-holding member can be operated. The hat-holding member may be made of metal, celluloid or any other suitable material. I have herein shown it as made of wire, and each arm is formed from a piece of wire bent to make a loop. This particular construction is not essential, however.

The tubular guiding member is shown at 5, and it will preferably have relatively unyielding walls. It may be made of metal, wood, fiber, celluloid or any other suitable material. It is provided with an aperture 6, through which the hat-holding member can reciprocate. This tubular guiding member is secured to, and is entirely inclosed by the attaching member above referred to, 75 which I preferably make of fabric.

The attaching member is of special construction designed not only to furnish means for attaching the hat fastener to the hat, but also to provide a protective covering for 80 the parts in which the hair will be liable to become entangled. This attaching member is herein shown as comprising two layers 7 and 8 of the fabric (velvet making a good fabric for this purpose) between which the 85 guiding member 5 is received, and said two layers will preferably be connected together by stitches 19 or otherwise, at the upper edge 9, and will be provided with an opening 10 at said upper edge through which the holding member 1 extends. The two layers 7 and 8 forming the attaching member extend below the lower end of the guiding member 5 a considerable distance thereby to form 90 protective wings 11, and these wings will 95 preferably be disconnected from each other. These protective wings 11 have sufficient extent so that when the hat-holding member is in its operative position as shown in Figs. 2 and 4, the head 4 thereof will be confined 100 between the wings 11. Said wings thus constitute a means for covering the head 4 and protecting it from becoming entangled in the hair. Moreover they provide a protection for the lower end of the guiding member 5 and thus prevent any liability of the latter being caught in the hair. Furthermore the upper edge 9 of the attaching member overlies and covers the upper end of the 105 guiding member. Since the attaching mem-

110

ber is made of some soft yielding material such as fabric it will be seen that when the hat fastener is in use and the hat-holding member is in operative position, there will be no projecting parts presented in which the hair can be caught.

- To prevent the hat-holding member from being withdrawn from the guiding member, I employ a stop member in the form of one or more stitches 12 which extend through the opening in one of the arms 2 and 3 and are secured in the upper edge 9 of the attaching member. The guiding member may be secured to the attaching member in any suitable way. The drawings show a guiding member having perforated wings 13 which are received between the layers 7 and 8 of fabric, and which may be secured to the fabric by stitches 14 passing through the perforations in said wings. Any other way of fastening the member to the attaching member might be employed, however, without departing from the invention.
- Having fully described my invention, what I claim as new and desire to secure by Letters Patent is:—
1. A hat fastener comprising a guiding member having relatively unyielding walls, a forked hat-holding member slideable through said guiding member and provided at one end with a head by which it can be moved in the guiding member, and an at-

taching member formed of two layers of fabric between which the guiding member is confined, and which is adapted to be sewed to a hat thereby providing the means by which the fastener is secured to said hat, said layers of fabric extending beyond the lower end of the guiding member thereby to form protecting wings between which the head of the hat-holding member is received when the latter is in operative position, and which protect said head and guiding member from being entangled in the hair.

2. A hat fastener comprising a guiding member, a forked hat-holding member slideable through the guiding member and provided at one end with a head, one arm of said hat-holding member being slotted, an attaching member formed of two layers of fabric between which the guiding member is confined, and to which said member is secured, the said layers extending below the lower end of the guiding member to form protective wings, and a stop member secured to the upper edge of the attaching member and extending through said slot.

In testimony whereof, I have signed my name to this specification, in the presence of two subscribing witnesses.

ANDREW O. SETHMAN.
